PATCHING APPARATUS AND METHOD

BACKGROUND OF THE INVENTION

This invention relates to the veneer and/or plywood art.

Wood veneer contains defects, such as knots or other marred or defective areas and is often upgraded by cutting the defect from the veneer and replacing the removed portion with a patch of veneer glued in place. The patches are typically cut from individual patch blanks or strips of veneer.

A veneer patching machine that uses pre-cut patch blanks is shown in U.S. Pat No. 2,336,704, the disclosure of which is incorporated herein by reference. As disclosed therein, a table of the machine supports a sheet of veneer to be patched and has an aperture over which a defective portion of the veneer sheet is positioned. A cutting and patching unit with portions above and below the table automatically clamps the sheet in position, cuts a portion of the veneer containing a defect from the sheet, forming an aperture, moves a veneer patch blank laterally from the top of a vertical stack of blanks into a position aligned with the aperture formed in the veneer sheet, cuts a patch blank to the shape and size of the aperture formed in the veneer sheet, and positions the cut patch in the aperture.

Other machines for patching veneer products are known which use strips of veneer from which patches are formed, rather than a stack of separate blanks, but patch blanks offer several advantages over strips, for example, the resultant debris produced in cutting the patches is necessarily in small pieces rather than in a continuous strip and therefore is easily ejected from the machine and disposed of, and high-grade long-length wood needed for patch strips is more expensive and more difficult to obtain than smaller patch blanks.

The wood used today by the plywood industry is requiring more and more repair to maintain an acceptable grade of product and as a result the amount of patching required is constantly increasing. Commercial embodiments of the veneer patching machine disclosed in the aforementioned patent normally used a stack of patch blanks about every 15 to 25 minutes of operation, and such machines are commonly operated 24 hours a day, 5 to 6 days per week through the year. It is, therefore, desirable that a large quantity of blanks be available for automatic feeding to the patching unit to minimize production interruptions.

SUMMARY OF THE INVENTION

One of the principal objects of this invention is the provision of a novel and improved patching apparatus using stacked pre-cut patch blanks and including means for automatically replacing an exhausted or used stack.

Another object of this invention is the provision, in a patching machine of the type that utilizes pre-cut patch blanks and a vertical magazine that holds a stack of individual blanks to be utilized by a cutting and patching unit, of a horizontal magazine for supplying stacks of patch blanks to the vertical magazine.

Another object of this invention is the provision of a novel magazine for a patching machine utilizing pre-cut patch blanks, which magazine can be conveniently loaded, will carry a large number of stacks of patch blanks arranged side-by-side in a row and will automatically feed stacks of patch blanks to a station where the individual patch blanks are removed one at a time and transported to a patch forming means of the patching machine.

Another object of this invention is to provide novel and improved methods of and apparatus for supplying stacks of patch blanks to a single-stack magazine of a patching apparatus, the stacks being arranged side-by-side in a row, moved together to position the leading end stack of the row in the single-stack magazine from which individual blanks are transported to a patch forming mechanism of a cutting and patching unit of the apparatus, and the remaining stacks moved away from the positioned end stack to provide a working clearance between the positioned end stack and the succeeding stack of the row.

The invention resides in certain manipulative steps and in certain constructions and combinations and arrangements of parts and further objects and advantages of the invention will be apparent to those skilled in the art to which it relates from the following description of the preferred embodiment described with reference to the accompanying drawings forming a part of this specification, and in which similar reference characters designate corresponding parts.

10 BRIEF DESCRIPTION OF THE DRAWINGS

FIG. 1 is a perspective view of a veneer patching apparatus embodying the present invention;

FIG. 2 is a partial perspective view of a vertical single-stack magazine of the apparatus;

FIG. 3 is a side elevational view with parts removed of a horizontal magazine assembly for plural stacks of patch blanks and the vertical single-stack magazine;

FIG. 4 is a plan view of the apparatus shown in FIG. 3;

FIG. 5 is an end elevational view of the apparatus of FIG. 3 taken from the right side;

FIG. 6 is an end elevational view of the apparatus of FIG. 3 taken from the left side; and

FIG. 7 is a diagram of an electrical control circuit for the apparatus.

25 DESCRIPTION OF PREFERRED EMBODIMENT

A veneer patching apparatus embodying the present invention is indicated generally at A in FIG. 1. The apparatus A includes a veneer cutting and patching unit B, a vertical magazine C for holding a stack of individual patch blanks of veneer for utilization by the cutting and patching unit B, and a horizontal magazine assembly D for supplying a stack of veneer patch blanks to the vertical magazine C upon utilization of a stack therein.

The veneer cutting and patching unit B includes mechanism for feeding the top patch blank from the stack in the vertical magazine C to a patch forming mechanism of the unit and is a commercial embodiment of the patching unit disclosed in the aforementioned U.S. Pat. No. 2,336,704. The cutting and patching unit B has a table 15 for supporting a sheet of veneer to be patched. Mechanisms for clamping the veneer sheet, cutting out a defect, transporting or feeding a patch blank from the single stack vertical magazine C, forming a patch therefrom, and placing the patch in the aperture formed in the sheet when the defect is removed also are a part of the cutting and patching unit and are disclosed in said U.S. Pat. No. 2,336,704.

50 The vertical single-stack magazine C, best shown in FIGS. 1 and 2, is a modification of the corresponding magazine shown in the aforesaid patent. Like the vertical magazine shown in the patent, the magazine C comprises a vertically movable platform 20 adapted to support a stack S of individual patch blanks BL and is normally biased in an upward direction to locate the top blank of the stack in a position to be fed to the patch forming mechanism. The platform 20 is supported on the upper end of a piston 22 of a pneumatic cylinder or reciprocating-type fluid-actuated motor 24 and moves vertically between guide plate portions 26 and 27 of the magazine C suspended from the unit B. The plate portions 26 and 27 guide the stack S in vertical movement as the upper blank of the stack is sequentially removed by the feed mechanism of the cutting and patching patch unit B. The upper end of the cylinder 24 is connected to the lower end of the depending plate 28 by a mounting plate 28.

The horizontal magazine assembly D, which feeds stacks of patch blanks to the vertical magazine C is best shown in FIGS. 1 and 3-6. The assembly includes a floor base 40 formed of a channel member 41 with three members 42 fixed thereto each having a leveling screw 43; an oscillatable magazine frame 46 that carries a patch blank stack pushing mechanism indicated generally at 48 and a magazine member 50 containing patch blank stacks; and front and rear pivotable support assemblies

52, 54, respectively, for the magazine frame. The magazine frame 46 is horizontally elongated and generally rectangular, with spaced parallel upper and lower horizontal tubular supporting members 56, 58, joined at their ends by spacer plates 60, 61 and by a front and a rear end plate 62, 63, respectively. A tubular cylindrical guide rod 66 is supported at opposite ends in the front and rear end plates and extends within the space between the upper and lower tubular supporting member 56, 58. The guide rod carries a tubular pusher bar guide 68 that encircles the rod and slides therealong relative to the magazine frame. A vertical pusher bar 70 is secured by a horizontal stem 71 to the pusher bar guide 68. The vertical pusher bar 70 is closely adjacent to side surfaces of the upper and lower tubular supporting members 56, 58 and is movable along with the pusher bar guide 68 longitudinally of the guide rod 66 along the length of the magazine 46.

A chain 74 is attached at two opposite ends to the pusher bar guide 68 and the chain loop so formed is trained about two sprockets 76, 77 at opposite ends of the magazine frame 46. Each of the end sprockets is rotatably supported on a stub shaft extending from the respective spacer plate 60, 61. A lower reach 74a of the chain 74 is also trained about two longitudinally spaced sprockets 78, 79 and extends downward between the two spaced sprockets, where it is trained about a sprocket 80 journaled for rotation near the extending end of a support arm 82 pivoted about a horizontal transverse shaft 83 at the front of the magazine assembly. The sprocket 80 is supported for rotation on a shaft 86 and a larger sprocket 88 is secured to the shaft for rotating the smaller sprocket 80. A rotary air motor 90 is secured at the distal end of a support arm 92 which is attached at one end to and extends from the support arm 82. A strut 93 connects the arms 82, 92 to hold them in fixed relationship. A sprocket 94 on the rotary air motor 90 drives the larger sprocket 88 through a chain 95. The air motor 90 can be driven in either direction to drive the chain 74 to advance or retract the pusher bar 70 along the tubular guide rod 66. Tension on the chain 74 can be adjusted by a screw 96 in a flange 97 at the end of the arm 82, which cooperates with the member 58 to establish the angular relationship of the arm 82 about the shaft 83.

The magazine member 50 is a channel or trough-shaped container for stacks of patch blanks, open at opposite ends. In the orientation shown, the magazine member has upper and lower horizontal flanges 100, 101 and a vertical web portion 102 extending between the flanges, forming with the magazine frame a support and passageway for a plurality of stacks of patch blanks. The width of the upper and lower flanges 100, 101 is slightly greater than the width of the patch blanks and the height of the web 102 corresponds with the height of the stacks. The stacks are supported by the lower flange 100 and are movable longitudinally of the magazine assembly but are restrained against lateral movement by the upper and lower tubular supporting members 56, 58 of the magazine frame and by the web 102 of the magazine member. The vertical pusher bar 70 moves within the magazine member 50 and, when advanced toward the vertical magazine C, engages an end one of the stacks in the magazine and slides the plurality of stacks within the horizontal magazine member toward the vertical magazine C. Because the ends of the magazine member 50 are open, the stacks can be pushed into the vertical magazine.

The magazine member 50 is supported on the frame at a front end by a front support plate 106 and adjacent the rear end by a rear support plate 108. Each of these plates is secured to the lower surface of the lower tubular support member 58 of the magazine frame 46, and both extend laterally to one side of the magazine frame so as to underlie the lower flange 101 of the magazine member 50. The lower front supporting plate 106 has a magazine member positioning member 110 (FIGS. 1 and 3) with an upper surface 110a upon which rests the front end of the lower flange 101 of the magazine member 50, an upwardly extending finger 110b at the front near corner, as viewed in FIG. 1, of the member 110 that engages a front edge of and locates the magazine, and an

upwardly extending member 50 in the magazine frame 46, front side flange portion 110c that restrains the lower part of the magazine member 50 against outward movement from the magazine frame 46. The lower rear support plate 108 has a 5 positioning member 112 thereon with an upper surface 112a that directly supports the lower flange 101 of the magazine member 50 and an upstanding front side flange portion 112b that engages a lower longitudinally extending outer portion of the magazine 50 to retain the lower portion against the magazine frame 46. In addition, the front end plate 62 of the magazine frame 46 has a vertical flange portion 62a that extends toward the vertical magazine C to provide an additional 10 positioning surface at the end of the magazine frame 46 for the magazine member 50 and which is closely adjacent and aligned with the vertically extending side portion 26 of the vertical magazine C. A hook member 114 is pivotally secured by a bracket 115 to the upper tubular supporting member 56 of the magazine frame 46 and hooks over the upper portion of the magazine member 50 to retain the upper portion against the magazine frame.

The magazine frame 46 is movable longitudinally toward and away from the vertical magazine C on the front and rear supports 52, 54 to transfer a stack of patch blanks to the vertical magazine and to then establish a working gap between the transferred stack and the next adjacent stack in the magazine. The front support 52 includes an upright leg 118 with depending lugs 119, 120 on opposite sides of the leg connected to a transverse pivot shaft 121 that is supported at opposite ends in spaced bearing blocks 122, 123 secured to the channel member 41 of the floor base 40. Upstanding lugs 126, 127 on opposite sides and at the top of the upright leg 118 are pivotally secured by a transverse shaft 128 to a mounting bracket 129 on the bottom of the lower front support plate 106. The rear support 54 includes a leg 132 identical in construction to the leg 118 and secured to a transverse pivot shaft 134 supported in spaced bearing blocks 135, 136 mounted on the channel member 41. The leg 132 is connected by an upper pivot 138 to a mounting bracket 139 beneath the rear support plate 108.

A toggle mechanism indicated generally at 142 is connected to the mounting bracket 139 at the upper pivot 138 of the leg 132 and, when actuated, can oscillate the magazine support relative to the base by virtue of the pivoted leg legs. The toggle mechanism 42 includes a front toggle link 144, a rear toggle link 145, a rear toggle link support arm 146, a tail air cylinder 147, and a toggle drive air cylinder 148. The front toggle link is connected at a front end to the upper pivot 138 and mounting bracket 139 of the leg 132. The rear end is pivotally connected to the front end of the toggle link 145 and to a clevis 152 on the end of a piston rod 153 of the toggle drive air cylinder 148. The toggle drive air cylinder 148 is oriented generally vertically, with the lower end pivotally supported by a bracket 155 on the channel member 41. The rear end of the 55 rear toggle link 145 is pivotally secured to the upper end of the rear toggle link support arm 146. The lower end of the arm 146 is pivotally secured by a bracket 158 to the base channel member 41. A piston rod 160 of the tail air cylinder 147 is also 60 pivotally secured to the upper end of the rear toggle link support arm 146. The tail air cylinder is pivotally secured to a mounting bracket 162. The extent to which the piston rod 160 projects from the tail air cylinder 147 determines an initial or reference position of the magazine frame 46 and positions the upper end of the rear toggle link support arm 146 at a given location. Actuation of the toggle drive air cylinder 148 will then oscillate the magazine frame 46 longitudinally relative to the rear toggle link support arm within the limits of the toggle mechanism as controlled by the stroke of the piston rod 70 153. Not only is the tail air cylinder 147 used to determine the reference position of the magazine frame but it also provides longitudinal movement away from the vertical magazine to facilitate removal and attachment of the magazine member 50 to the frame 46. It also functions as an air spring during operation to provide a safety function by limiting the force that can

be generated by the toggle linkage between the rear toggle link support arm 146 and the mounting bracket 139 at the upper end of the leg 132. Thus, while the toggle mechanism can create extremely great force at the breakover point of the mechanism, the force will necessarily be limited to the force developed by the tail air cylinder 147 that locates the rear toggle link support arm 146.

In preparing the machine for operation, the magazine member 50 is loaded with a plurality of stacks S of patch blanks, each stack side-by-side, and the magazine member is placed against the magazine frame 46 with the front end of the magazine member positioned by the positioning member 110. The troughlike construction of the magazine member 50 facilitates loading by permitting side-by-side a stacks of cut blanks to be slid as a group on their sides directly into one end of the magazine member while the magazine member is lying on its side as to support the stacks on the web portion 102. This is especially convenient when a row of stacks is formed by cross cutting a stack of long strips. The row is then slid endwise from the cutting mechanism into the magazine member, which is then placed on the magazine frame. By way of example, the magazine member 50 typically has an approximate capacity of 2400 1/10-inch thick patch blanks 2% inches wide by 4% inches long, in other words 22 stacks of 110 patches each. During the loading, the magazine frame 46 is retracted a substantial distance from the vertical magazine C by the tail air cylinder 147. In addition, the toggle drive air cylinder 148 is actuated to retract the piston rod and pull the front and rear toggle links 144, 145 downward at their juncture. Both of these actions cause the support legs 118, 132 to pivot to the left as viewed in FIGS. 1 and 3.

Once the magazine member 50 is in position on the frame 46, the tail air cylinder 147 is actuated to position the rear toggle link support arm 146 at a location where actuation of the toggle drive air cylinder 148 will move the horizontal magazine assembly a distance sufficient to position the front end immediately adjacent to the vertical magazine C. With the magazine assembly in a forward position as a result of actuation of the toggle drive air cylinder 148, the air motor 90 is operated to advance the pusher bar 70 along the guide rod 66 toward the vertical magazine assembly. The pusher bar 70 engages an end one of the plurality of stacks in the magazine and advances the row of stacks forward so that an end stack at the front of the row is moved onto the elevator platform 20 of the vertical magazine C, which elevator platform is in a lowered position. When the end stack abuts the vertically extending side portion 27 of the vertical magazine, movement of the pusher bar is stopped. The toggle drive air cylinder 148 is actuated to retract the piston rod and to again pull the front and rear toggle links 144, 145 downward at their common juncture, retracting the horizontal magazine assembly from the vertical magazine C to provide a slight gap or working clearance between the stack of patch blanks now in the vertical magazine C and the next adjacent stack at the end of the horizontal magazine. This gap is preferably about three-eighths inch. The fluid actuator 24 of the vertical magazine C then moves the elevator platform 20 and stack of patch blanks upward until the upper patch blank engages a stop associated with the patch feeding mechanism of the cutting and patching unit. During operation of the patching unit, patch blanks are used one at a time from the stack in the vertical magazine, the actuator 24 continuously biasing the elevator platform upward and advancing it as patch blanks are taken from the top of by the feed mechanism of the patching unit. When all patch blanks of the vertical magazine have been used, the elevator platform is withdrawn, the toggle drive air cylinder 148 actuated to extend the piston rod and move the horizontal magazine assembly forward, and the cycle is repeated.

The manner in which the machine is controlled and operated to perform the functions and operate in the manner described above will be better understood in connection with the control circuit of the machine diagrammatically shown in FIG. 7. The circuit is shown in the form of a ladder diagram

with the general function of various elements of the circuit indicated to the right of the line in which the element appears in the circuit. Individual lines connected across parallel vertical circuit lines are numbered along one side of the circuit diagram and the line number in which the switch actuated by a given relay is located is indicated in parenthesis in conjunction with the indicated function of the relay along the side of the diagram. If a switch is normally closed, the number of the line in which it is located is underlined where it is indicated in conjunction with the function performed by the associated relay. Contacts associated with timer relays are indicated as either "N.C.-T.O." (normally open-timed closed) or "N.C.-T.O." (normally closed-timed open). In the following description the circuit line member, in which the elements referred to are located, is indicated in parenthesis.

The control circuit is divided into three parts, a motor circuit, a patcher control circuit, and a feeder control circuit. Three electrical lines L1, L2, L3 connected through a circuit breaker CB to a source of 440-volt 3 phase 60-cycle electrical current supply power to a motor MTR through three motor starter contacts M-1, M-2, M-3 operable from a motor starter relay M (line 12). The motor MTR operates the veneer patching machine.

25 Patcher control and feeder control portions of the circuit are connected to the input lines L2, L3 by a control transformer T1 lines 4 to 6. Two lines L4, L5 from the transformer T1 are connected to a clutch/brake control unit of the patching machine, which is used to control the mechanical cutting, patching and patch feeding mechanisms. The clutch/brake control unit is indicated by the dotted line area 170 of the wiring diagram, is conventional, and is not described in detail. Three principal circuit lines L6, L7 and L9 extend along opposite sides of the circuit. The line L7 extends 30 along both the patcher control and the feeder control portions of the circuit. The line L6 terminates within the patcher control portion of the circuit but is connected by a line L8 to the principal line L9 that parallels the line L7 in the feeder control portion of the circuit. A line L10 is connected across lines L4 and L5 and an indicator lamp IL indicates that power is being supplied. The remaining elements of the circuit diagram will be described in conjunction with their operation.

35 The horizontal magazine D is first loaded by securing the magazine portion 50 to the magazine frame 46 in the manner previously described. During this operation the pusher bar 70 must be in retracted position. This is accomplished by switching a feeder selector switch 1SS (line 17) from an automatic position to a load position which permits manual operation of the control. As will be seen from lines 14, 17, and 26 of the circuit diagram, the switch 1SS includes contacts in each of the three mentioned lines. Three positions of the switch are possible and the position of the switch operator in which each contact element is closed is indicated by the letter X at the switch contacts and the positions of the switch at which the contacts are open is indicated by the letter O. Thus, when the switch 1SS is set to automatic, as indicated in line 17, only the contact in line 17 is closed. As the switch is moved from automatic to loading (to the left in the diagram), it passes an intermediate position at which only the contact of line 14 is closed. In the load position, only the contact in line 26 is closed.

40 By manual operation, the operator actuates a three-way manually operated air control valve (not shown) to retract the pusher bar to the retracted position by operating the rotary air motor 90. The operator also actuates a manual four-way valve (not shown) of an air control circuit that operates the tail air cylinder 147 to pull the entire magazine frame 46 away from the vertical magazine C. This facilitates installation of the magazine member 50. The magazine member 50 is registered 45 on the magazine frame 46 and the manual valve controlling the tail cylinder 147 is actuated by the operator to move the magazine frame 46 and magazine member 50 carried thereby toward the vertical magazine C to a reference position at which the end of the horizontal magazine is slightly spaced 50 from the vertical magazine. In this position a safety interlock

microswitch 2LS (line 12) is closed. A stop switch 1PB (line 12) for the motor MTR can now be unlocked (i.e., closed) to restore power to the sequence timing portion or feeder control part of the circuit. Thus, line L4, L6, L8 and L9 are interconnected.

A jog button with two sets of contacts is provided on a control panel and is indicated at 3PB (lines 26, 27) in the control circuit. Manual actuation of the jog button 3PB energizes solenoids SOL-4 and SOL-5 as long as the switch 1SS is in the load position. Solenoid SOL-4 operates an air valve that controls the toggle drive air cylinder 148, positioning the valve so that air will be supplied to the cylinder to move the magazine frame 46 forward or toward the vertical cylinder C and position the end of the magazine directly adjacent thereto. The solenoid SOL-5 operates a valve that controls the air motor 90, causing the motor to advance the pusher bar toward the vertical magazine to push the row of stacks of patch blanks in the horizontal magazine until an end stack is positioned in the vertical magazine. Upon release of the jog button 3PB, deenergization of the solenoid SOL-4 will reposition the associated air valve in its original position, retracting the piston rod of the toggle drive air cylinder 148 and withdrawing or retracting the horizontal magazine a slight distance from the vertical magazine to provide an operating clearance between the stack of patch blanks in the vertical magazine and the next adjacent stack within the horizontal magazine.

The operator now returns the feeder selector switch 1SS to the automatic position. In its movement from the load position to the automatic position, the switch closes the associated contacts (line 14) that energize the unlatch coil 1CRU (line 16) of a control relay 1CRL (line 15) that controls the cycling of the patch feeding mechanism and the mechanism that feeds the stacks of patches to the vertical magazine. The unlatching of the control relay 1CRL returns a normally closed set of contacts 1CRL-1 (line 10) to their normally closed condition so that closing of a cycle start switch 1FS (line 10) by the operator will energize a control relay (not shown) of the clutch/brake unit to operate the patching unit. The control relay of the clutch/brake unit is kept energized during the patching operation by the cam switch 1LS (line 11), which is cammed closed by the patching unit once operation is begun.

During operation, patch blanks of the stack in the vertical magazine C are used by the patching unit each time a patching operation is cycled by the operator closing switch 1FS. When the last blank of the stack in the vertical magazine is used a limit switch 3LS (line 15) associated with the air cylinder of the vertical magazine is closed. When the operator cycles the patching unit limit switch 4LS (line 15) in series with the limit switch 3LS is closed to latch the control relay 1CRL (line 15). Latching of this control relay (a) opens normally closed contacts 1CRL-1 (line 10) to open the start cycle circuit and prevent further operation of the patching unit, (b) opens normally closed contacts 1CRL-2 (line 23) to deenergize solenoid SOL-3 which permits a solenoid actuated valve that controls the cylinder 24 of the vertical magazine to retract and lower the elevator platform 20 and (c) closes normally open contact 1CRL-3 (line 18) to energize five timer relays 1TR (line 18), 2TR (line 19), 3TR (line 20), 4TR (line 21) and 5TR (line 22). Relay 1TR closes contact 1TR-1 (line 24) to energize solenoid SOL-4 which operates a valve to cause the toggle drive air cylinder 148 to extend the piston rod 153 and advance the horizontal magazine D toward the vertical magazine C to place the end of the horizontal magazine directly adjacent the vertical magazine. Timer relay 2TR is energized after a delay sufficient to assure that the elevator plate of the vertical magazine has been retracted to close normally open contact 2TR-1 (line 25). This completes a circuit through normally closed contact 3TR-1, which has not yet been timed open due to a timed delay in energizing relay 3TR, to energize the solenoid SOL-5 and operate the solenoid controlled valve associated with the rotary air motor 90 to advance the pusher bar forward, moving the row of stacks in the horizontal magazine toward the vertical magazine to position

the end stack on the elevator platform 20. After a suitable time delay, timer relay 3TR is closed, opening normally closed contact 3TR-1 to deenergize solenoid SOL-5, stopping operation of the rotary air motor 90. Subsequent energization of the relay 4TR after a predetermined time delay opens normally closed contacts 4TR-1 (line 24) to deenergize solenoid SOL-4 permitting the control air valve for air cylinder 148 to return to its original position, which causes the toggle drive air cylinder 148 to withdraw the piston rod 153 and move the magazine frame 46 away from the vertical magazine C. This creates a gap of approximately three-eighths inch between the stack of patch blanks positioned in the vertical magazine and the next adjacent stack in the horizontal magazine, thereby providing a working clearance between the row of stacks in the horizontal magazine and the stack of blanks transferred. Subsequently, relay 5TR times out to end the feeder cycle by closing contact 5TR-1, which energizes the unlatch relay 1CRU (line 16), opening contact 1CRL-3 (line 18) and permitting contacts 1CRL-1 (line 10) and (line 23) to return to the normally closed condition. Contact 1CRL-2 energizes solenoid SOL-3 to actuate the air cylinder 24 and raise the elevator platform 20 of the vertical magazine to position the top of the stack of patch blanks against a stop of the feed mechanism of the patching unit.

When the last stack of patch blanks is fed from the horizontal magazine in the manner above described, a limit switch 5LS (line 17) is closed to connect a circuit to a warning light 1LT (line 17) on the control panel to indicate that the horizontal magazine is empty. This light is turned off by the operator turning the selector switch 1SS (line 17) to the load position. If the horizontal magazine is not reloaded while the last stack of patch blanks is being used, control relay 1CRL (line 15) is latched as previously described when limit switches 3LS and 4LS are closed, but because the feeder switch 1SS is set to load position, the timer circuit of lines 18 to 22 does not operate. As a result, the patch cycle stops with the elevator plate 20 of the vertical magazine in a down position. At this point, the stop button 1PB (line 12) should be locked open for safety purposes and to deenergize the entire timer sequence circuit, and the horizontal magazine should be reloaded.

From the foregoing description and from the accompanying sheets of drawings it will be apparent that there has been provided by this invention improved methods and apparatus for patching veneer, and an improved magazine construction, by which the previously enumerated objects and advantages have been attained.

Although the invention has been described in a detailed manner and with reference to a specific embodiment and specific method, and as used with a specific veneer patching machine, it will be understood that various modifications or alterations may be made therein, and that the invention can be embodied in or used with different patching machines without departing from the spirit and scope of the invention, as set forth in the appended claims.

I claim:

1. In apparatus for patching veneer and the like, means for making veneer patches from precut patch blanks, a vertical feed magazine adapted to support a stack of patch blanks, a horizontal magazine with one end adjacent the vertical magazine for supporting a row of side-by-side stacks of patch blanks adjacent the vertical feed magazine, power means to advance the row of side-by-side stacks carried by the horizontal magazine toward the vertical magazine, means for selectively operating said power means to transfer a stack of patch blanks from the horizontal magazine to the vertical magazine, and means providing a clearance between a stack of patch blanks transferred to the vertical magazine and the leading stack of patch blanks in the horizontal magazine.

2. In a patching apparatus for making veneer patches from precut patch blanks, a vertical feed magazine for supporting a stack of patch blanks to be used by patch forming means, a horizontal magazine with one end adjacent the vertical

magazine for supporting a plurality of stacks of patch blanks, means supporting said horizontal and vertical magazines for relative movement toward and away from each other, means to move stacks of patch blanks carried by the horizontal magazine relative thereto toward the vertical magazine to transfer an end stack thereof to the vertical magazine, and means to relatively move the horizontal and vertical magazines one toward the other during each transfer of a stack of patch blanks to the vertical magazine.

3. Apparatus for supplying veneer patch blanks to a cutting and patching unit comprising feed means for advancing patch blanks of a stack vertically: a magazine member for holding stacks of patch blanks; means supporting said magazine member for movement toward and away from said feed means; means to selectively move said magazine member toward said feed means to facilitate the transfer of a stack of blanks from said magazine member to said feed means and to thereafter move said magazine member away from said feed means to establish a clearance between the transferred stack and the leading stack remaining in said magazine member; a guided pusher movable along said magazine member for engaging an end one of the stacks of patch blanks carried by said magazine member remote from said feed means; and drive means to advance said pusher and stacks of patch blanks toward said feed means.

4. In apparatus for patching veneer and the like, a vertical magazine for advancing patch blanks to a cutting and patching unit, a container for a row of stacks of patch blanks, a frame for said container supported for oscillation toward and away from said vertical magazine to facilitate feeding a new stack of blanks thereto and to thereafter establish a clearance between the stacks carried by said container and a stack transferred to said vertical magazine, power means to selectively move said frame and container toward and away from said vertical magazine, a guided pusher carried by said frame and movable relative thereto for advancing stacks of patch blanks carried by said container toward said vertical magazine, power means to selectively advance said pusher along said frame, and control means for automatically sequencing the feeding of successive stacks of patch blanks to the vertical magazine.

5. In apparatus for patching veneer and the like, a vertical magazine for holding a stack of patch blanks, means for raising said stack to position patches adjacent patch forming means, an elongated horizontal magazine member with one end adjacent the vertical magazine for supporting a row of stacks of patch blanks, a frame for said horizontal magazine member, a base supporting said frame, means connecting said frame to said base for longitudinal movement of said frame toward and away from said vertical magazine, said means including longitudinal spaced upright pivot arms secured at upper ends to said frame and at lower ends to said base, power means including a fluid motor connected between said base and said frame to selectively move said frame and horizontal magazine member toward and away from said vertical magazine, a guided pusher movable along said magazine member for advancing stacks of patch blanks carried by said horizontal magazine member toward said vertical magazine, and power means to selectively advance said pusher along said magazine member, whereby a stack of patch blanks can be transferred from the horizontal magazine member to the vertical magazine by moving the horizontal magazine member to a position directly adjacent the vertical magazine, advancing the guided pusher to move a stack of patch blanks from the horizontal magazine member to the vertical magazine, and thereafter moving the horizontal magazine member away from the vertical magazine to establish a gap between the transferred stack and the adjacent stack in the horizontal magazine member.

6. In a veneer patching apparatus, a vertical magazine for holding a stack of patch blanks; means for raising said stack to position patches adjacent patch forming means; and elongated horizontal magazine member with one end adjacent the vertical magazine for supporting a row of stacks of patch blanks; a

frame for said horizontal magazine member; a base supporting said frame; means connecting said frame to said base for longitudinal movement of said frame toward and away from said vertical magazine, said means including longitudinally spaced upright pivot arms secured at upper ends to said frame and at lower ends to said base; power means to selectively move said frame and horizontal magazine member toward and away from said vertical magazine including an upright toggle support arm extending from said base adjacent one of said upright pivot arms, a toggle linkage between said toggle support arm and said adjacent upright pivot arm, a first fluid actuator with a reciprocable piston connected between said toggle support arm and said base and a second fluid actuator with a reciprocable piston connected between the toggle linkage and said base; a guided pusher carried by and movable along said frame for advancing stacks of patch blanks carried by said horizontal magazine member toward said vertical magazine; and power means to selectively advance said pusher along said frame; whereby a stack of patch blanks can be transferred from the horizontal magazine member to the vertical magazine by moving the horizontal magazine member to a position directly adjacent the vertical magazine, advancing the guided pusher to move a stack of patch blanks from the horizontal magazine member to the vertical magazine, and thereafter moving the horizontal magazine member away from the vertical magazine to establish a gap between the transferred stack and the adjacent stack in the horizontal magazine member.

7. In a veneer patching apparatus, a vertical magazine for holding a stack of patch blanks; means for raising said stack to position patches adjacent patch forming means, an elongated horizontal magazine member with one end adjacent the vertical magazine for supporting a row of stacks of patch blanks; a frame for said horizontal magazine member; a base supporting said frame, means connecting said frame to said base for longitudinal movement of said frame toward and away from said vertical magazine, said means including longitudinally spaced upright pivot arms secured at upper ends to said frame and at lower ends to said base; power means to selectively move said frame and horizontal magazine member toward and away from said vertical magazine including an upright toggle support arm extending from said base adjacent one of said upright pivot arms, a toggle linkage between said toggle support arm and said adjacent upright pivot arm, a first fluid actuator with a reciprocable piston connected between said toggle support arm and said base and a second fluid actuator with a reciprocable piston connected between the toggle linkage and said base; a guided pusher carried by and movable along said frame and horizontal magazine member toward and away from said vertical magazine, said pusher being carried by a guide rod and being secured to a drive chain extending along said frame, and power means including a motor drive and a drive sprocket for said chain to selectively move said pusher along said frame, whereby a stack of patch blanks can be transferred from the horizontal magazine member to the vertical magazine by moving an end of the horizontal magazine member to a position directly adjacent the vertical magazine, advancing the guided pusher to move a stack of patch blanks from the horizontal magazine member to the vertical magazine and thereafter moving the horizontal magazine member away from the vertical magazine to establish a gap between the transferred stack and the adjacent stack in the horizontal magazine member.

8. A magazine assembly for supplying veneer patch blanks to patching apparatus and constructed to hold a row of stacks of patch blanks, said magazine assembly comprising an elongated frame, an elongated channel-shaped magazine member open at opposite ends and removably carried by the frame for supporting and containing a row of side-by-side stacks of patch blanks, a stack pusher supported on said frame for contact with an end one of the stacks in the magazine member and for longitudinal movement relative to the frame and along said magazine member to advance the stacks through an open end

of said magazine member, a power drive to advance said stack pusher along said magazine member, a support for said frame, and a power actuator to move said frame longitudinally relative to said support.

9. A magazine assembly for supplying veneer patch blanks to patching apparatus, comprising a support, a frame carried by said support for relative reciprocable movement, a carrier for stacks of patch blanks supported on said frame, means to advance said stacks relative to said carrier toward an end thereof and an actuator operatively connected to said frame to reciprocate said frame and carrier relative to said support, whereby said end of the carrier can be selectively positioned directly adjacent a patching apparatus for the transfer of a stack of patches thereto and subsequently spaced therefrom.

10. Apparatus for supplying veneer patch blanks to a vertical magazine of a veneer patching apparatus, said apparatus comprising a base, an elongated carrier frame, spaced upright members extending between and connecting the frame to the base, pivotal connections between said supports and said base and frame, means including an actuator connected between said base and frame to reciprocate said frame relative to the base, a carrier removably supported on said frame for holding stacks of patch blanks, a member supported for movement along said frame relative to said carrier and engageable with a stack of patch blanks carried by said carrier, and drive means to move said member along the frame to advance stacks of patch blanks toward one end of said carrier.

11. Apparatus for supplying veneer patch blanks to a vertical magazine of a veneer patching apparatus, said apparatus comprising a support, an elongated carrier frame, spaced members extending between and connecting the frame to the support, pivotal connections between said spaced members and said support and frame, a toggle joint operatively connected between the support and the carrier frame to move the frame longitudinally relative to the support when straightened or flexed, power means connected to said toggle joint selectively operable to straighten and flex said toggle joint, an elongated carrier supported on said frame for supporting stacks of patch blanks, a slidable pusher carrier on a guide on said frame for movement longitudinally thereof and constructed to engage a stack of patch blanks supported by said carrier, and drive means carried by said frame for moving said pusher along said guide to advance stacks of patch blanks along said carrier to one end thereof.

12. A method of supplying veneer patch blanks to a vertical magazine of a veneer patching apparatus, which comprises aligning and supporting a plurality of stacks of individual patch blanks side-by-side in a horizontal row, advancing the

row of stacks to position an end stack of said row in a vertical magazine of a veneer patching apparatus, and thereafter moving the row of stacks minus said end stack positioned in the vertical magazine in a direction away from the magazine to space the row of remaining stacks from said positioned end stack to provide a working clearance therebetween.

13. A method of supplying stacks of veneer patch blanks successively to a single stack support of a veneer patching apparatus, which comprises slidably supporting a plurality of stacks of individual patch blanks side-by-side in a horizontal row on a multiple-stack support, sliding the row of stacks relative to the multiple-stack support to advance an end stack of said row from said multiple-stack support to the single-stack support and subsequently carrying the remaining supported stacks away from said single-stack support to space the stacks on said multiple-stack support from the stack on said single-stack support.

14. A method of supplying veneer patch blanks to a veneer patching apparatus, which comprises providing a first stack of blanks at a veneer patching machine, removing patch blanks from said first stack and moving the remaining blanks vertically, providing a row of additional stacks of patch blanks with an end stack of said row adjacent to and spaced from said first stack, advancing the stacks of said row when all patch blanks of said first stack are removed to move said end stack into the position previously occupied by said first stack, and then moving said row of stacks minus said end stack away from said position to provide a clearance between the row and said end stack.

15. Apparatus for supplying veneer patch blanks to a cutting and patching unit comprising feed means for advancing patch blanks of a stack vertically: a magazine member for holding stacks of patch blanks; means supporting said magazine member for movement toward and away from said feed means; a guided pusher movable along said magazine member for engaging an end one of the stacks of patch blanks carried by said magazine member remote from said feed means; drive means to advance said pusher and stacks of patch blanks toward said feed means; power means to selectively move said magazine member toward said feed means to facilitate the transfer of a stack of blanks from said magazine member to said feed means and to thereafter move said magazine member away from said feed means to establish a clearance between the transferred stack and the leading stack remaining in said magazine member; and control means for effecting operation of said drive means and said power means in predetermined sequence.

UNITED STATES PATENT OFFICE
CERTIFICATE OF CORRECTION

Patent No. 3,545,648 Dated December 8, 1970

Inventor(s) PER O. SKOOG

It is certified that error appears in the above-identified patent and that said Letters Patent are hereby corrected as shown below:

On the page immediately following the drawings containing the Abstract, the spelling of the Inventor's name is misspelled. It should be --PER OLOF SKOOG--.

Column 9, line 51, "longitudinal" should be --longitudinally--

Column 9, line 73, change "and" to --an--.

Signed and sealed this 6th day of April 1971.
